UNITED STATES PATENT OFFICE.

JAMES S. RAY, OF EAST HADDAM, CONNECTICUT.

DESIGN FOR COFFIN-HANDLE SOCKET.

Specification forming part of Design No. 6,734, dated June 24, 1873; application filed June 16, 1873.

To all whom it may concern:

Be it known that I, JAMES S. RAY, of East Haddam, in Middlesex county, in the State of Connecticut, have invented a new and original Design for a Coffin-Handle Socket, of which the following is a specification:

Figure 1 is a face view of my new design for the socket of a coffin-handle. Fig. 2 is a profile longitudinal section thereof, and Fig. 3 a profile transverse section thereof.

Similar letters of reference indicate corresponding parts of the figures.

This invention relates to a new design for a rectangular socket of a coffin-handle; and consists in the general configuration of the parts herein shown and described.

The socket is, as above stated, of rectangular outline, and has a rectangular raised central portion, a, which is, by a cross-band, b, divided into two halves, one of which is partly and the other entirely slit or depressed for the reception of the handle. The raised central part a has square corner-pieces d, which are ornamented by angle-lines or borders, as shown. A narrow slightly-elevated border embraces the entire elevated portion a. The sides and ends of the sockets slant out from the elevated portion a toward the base in hollow curves, which are, at the corners, and also at the middle parts of the long sides, ornamented by upright corrugations e that extend up from the base toward the border of the elevated portion a, and also at the corners toward the miter-line of the adjoining sides and ends. Otherwise the central portion and the slanting sides may be ornamented by scrolls or other suitable design.

I claim—

The design for the socket of a coffin-handle, as shown.

JAS. S. RAY.
